TAPE DISPENSING MACHINE

Filed April 17, 1930

By his Attorney Thompson

UNITED STATES PATENT OFFICE

1,921,625

TAPE DISPENSING MACHINE

Louis Link, New York, N. Y.

Application April 17, 1930. Serial No. 444,930

4 Claims. (Cl. 271—2.4)

My invention relates to improvements in paper strip dispensers, and more particularly, has reference to and is illustrated in the accompanying drawing in its application to a gummed or adhesive paper strip dispenser device, such as is adaptable for closing paper packages and the like, and is an improvement on the dispenser disclosed in my co-pending patent application S. N. 396,999.

10 Referring to the accompanying drawing, Fig. 1 illustrates in perspective, parts being broken away, a part of a dispensing machine showing an embodiment of my invention. Fig. 2 is an enlarged longitudinal sectional detail illustrating parts mounted upon the shaft. Fig. 3 illustrates part of the paper feed mechanism, partly in section, and parts broken away. Fig. 4 is a detail in perspective illustrating part of the strip forming and guiding mechanism. Fig. 5 illustrates, partly in section and parts broken away, part of the finger control for operating the device. Fig. 6 is a view looking from right to left at Fig. 5, and Fig. 7 is a sectional detail of the water box and brush moistener mechanism.

15 20 25 30 35 40 45 50 55

8 indicates the frame of the machine, having a circular frame-like portion 9, projected laterally therefrom, with a series of holes 10, for engagement by the pin 11, in the lever 12 for predetermining the length of gummed strip to be torn off. Through the center of the frame is projected the spindle 14, having rotatably mounted thereon at the outer end, a lever 15, said lever having a counter weight 17, and being connected at the top with another lever 18, by a pin 19, which pivotally retains the finger portion 20, for dispensing the strip.

The finger portion 20, pivotally mounted at 19, upon the two arms 15, 18, is provided with a depending portion 21, which when the finger portion 20, is pulled leftwardly looking at Fig. 1, bears against the periphery of a disc 13, secured to spindle 14 by a pin 16 thereby rotating the same counter clockwise and feeding the strip. 22 indicates a pad, or bumper, at the back of the finger piece 20, so that upon the return stroke, the blow is cushioned against the face of the stop 23, which has a forwardly projecting spring portion 24, that prevents rebound leftwardly of the lever 15, after it has struck the stop. This stop 23 is part of, or secured to the lever 12, which is mounted on the spindle 14, as shown in Fig. 2, and which is preferably made of resilient material to permit the end 12' to be pulled

ring 9 for changing engagement of the pin 11, with the holes 10 therein, thus shifting the stop 23, at any desired point around the circle and thereby varying the swing or stroke of the finger piece and lever 20, 15 respectively. 24' serves as an indicator or pointer, if desired, for indicating the length of strip to be cut.

Upon the shaft 14 is secured a housing 25, at the right end of which is a reduced portion 26 serving as a bearing for the lever 12, and for seating in the frame 8. This housing is preferably secured to the frame 8 at three points with screws 27, and has an internal circular chamber 28, within which may be secured the coiled flat spring 29 at one end, as indicated at 30, the opposite end being secured at 31, to an off-set 32' from the lever 18, and at the outer end of the shaft 14, is provided the ring 32, penetrated by the pin 16, for holding the combination referred to in proper relation upon the shaft 14; from all of which, it will be seen that by pulling the finger end 12' of the lever 12 toward the operator, the said lever 12 may be moved to the right or left, thus increasing or decreasing respectively, the sweep of the lever 15, 18, which is pulled against the action of the spring 30, at the same time, the engaging edge 21 of the finger piece 20, gripping the periphery of the disc 13 and rotating anticlockwise, the roll of gummed strip within the machine, passing the free end leftwardly between the rollers 33, 34, shown in Fig. 3, the counter weight 17, serving to return the lever 15, 18, to the stop 23, at whatever position it may be held by the pin 11. Rollers 33, 34 are driven from shaft 14 in any suitable manner as by a train of gears A, B, C and D shown somewhat diagrammatically in Fig. 3.

The free end 35 of the strip after passing between the rollers 33, 34, is raised in the center 85 by the tapered elevation piece 36, shown to advantage in Fig. 4, thereby slightly channeling and stiffening the strip to insure proper rigidity of the strip for feeding of the same leftwardly, the cutting-off mechanism being preferably substantially as shown in my co-pending case referred to.

The water-box for moistening the gummed strip beneath, as it feeds out of the machine, is 105 shown to advantage in Fig. 7, where the water level is preferably as indicated at 37, the bristles 38, of the brush extending upwardly to contact with the under gummed surface of the strip, the brush is backed by an inwardly projecting 110

portion 39 of the water chamber 40, and is preferably at the base, with a metallic holder 41, for the bristles, and projecting inwardly from the bottom of the chamber 40, is preferably provided a tongue or tongues 42, which snap over the top edge of the metallic holder 41, thus holding the same properly seated upon the base 43, and when it is required to remove the brush, the bristles 38 are pressed back against the spring-like support 39, thus moving the holder 41 free from engagement with the prongs 42, allowing the brush to be pulled upwardly and withdrawn.

Of course, it will be understood that various modifications may be made in the construction 15 and arrangement of parts without departing from the spirit of invention as claimed.

I claim:

1. In a device of the class described, a chamber for a roll of gummed paper and a spindle 20 projecting therefrom, a lever axially mounted in relation to said spindle and having a pivoted finger piece at the free end for rotating the same about said spindle as a center, and in combination with said lever, a disc and means 25 connected therewith for feeding said strip whereby when said finger piece is operated and said lever moved, said disc is rotated, and an adjustable stop for controlling the length of throw of said lever.
- 30 2. In a strip feeding mechanism, a casing, a support therein for a strip of material to be fed, feed rollers engageable with the strips for feeding the strip from the machine, a spindle, an arm freely movable about said spindle as

an axis, a member fixed to said spindle, driving connections between said spindle and said rollers, and pivoted finger engageable means on said arm engageable with the member fixed to the spindle when the arm and pivoted means are 80 moved in one direction.

3. In a machine of the character described, a casing, a support therein for a strip to be fed, feeding means engageable with the strip to feed 85 said strip, a spindle, an arm pivoted for free movement thereon, a member fixed on the spindle, a hand engageable member movably mounted on the arm and engageable with said member on the spindle upon movement of the arm and member in one direction, operative connections between the spindle and strip feeding means, spring means for rotating the arm in one direction, and adjustable means to limit said movement.

4. In a strip feeding machine, a casing, a strip 95 support therein, strip feeding means, a spindle, operative driving connections between the spindle and feeding means, a member pivoted for free movement about said spindle, a member fixed to the spindle, spring means for swinging the pivoted member in one direction, adjustable means for limiting said movement, a handle pivoted to said pivoted member and movable therewith, and means carried by the handle and engageable with the member fixed to the spindle 100 when said handle and pivoted member are swung in a direction of movement opposite to the spring actuated movement.
